UNITED STATES PATENT OFFICE

2,608,337

LADDER HINGE

Oscar E. Nehler, Lincoln, Nebr.

Application February 9, 1948, Serial No. 7,222

1 Claim. (Cl. 228—68)

This invention relates to new and useful improvements in ladders and the primary object of the present invention is to provide a combination step and extension ladder.

Another important object of the present invention is to provide a combination step ladder and extension ladder that includes a novel and improved hinge which is quickly and readily applied to or removed from a pair of ladder sections in a convenient manner.

A further object of the present invention is to provide a combination step and extension ladder including a pair of hinged ladder sections and novel and improved means for holding the ladder sections in an extended position.

A still further aim of the present invention is to provide a ladder hinge that is simple and practical in construction, strong and reliable in use, small and compact in structure, neat and attractive in appearance, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a fragmentary perspective view of a ladder constructed in accordance with the present invention, and showing the same in a locked and extended position for use as an extension ladder:

Figure 2 is a fragmentary perspective view of the ladder constructed in accordance with the present invention, and showing the same in an unlocked position for use as a step ladder:

Figure 3 is a perspective view of one of the hinge members used in conjunction with the present invention:

Figure 4 is an enlarged longitudinal vertical sectional view taken substantially on the plane of section line 4-4 of Figure 7.

Figure 5 is an enlarged transverse horizontal sectional view taken substantially on the plane of section line 5—5 of Figure 4.

Figure 6 is a longitudinal vertical sectional view taken substantially through the center of the hinge member used in conjunction with the present invention: and

Figure 7 is a fragmentary front elevational view of the present ladder structure in position for use as an extension ladder.

Referring now to the drawings in detail, wherein for the purpose of illustration, there is dis-

closed a preferred embodiment of the present invention, the numeral 10 represents the present combination step and extension ladder generally, comprising a lower or forward section 12 and an upper or rear section 14. The lower section 12 is provided with a pair of spaced, parallel substantially rectangular side rails 16 that are connected by a plurality of longitudinally spaced rungs, the upper of which is designated by the numeral 18. The upper section 14 is also provided with a pair of spaced, parallel substantially rectangular side rails 20 that are connected by a plurality of longitudinally spaced rungs including a lower rung 22.
Frictionally and slidably engaging the upper ends of the side rails 16, is a pair of channel shaped lower anchor members 24 the upper rear edges of which are hinged as at 26 to the lower rear edges of a pair of upper channel shaped anchor members 28 that slidably and frictionally engage the lower ends of the upper side rails 20.
Projecting outwardly from the inner sides 30 and 32 of the lower anchor members 24 and the upper anchor members 28, are lower pivot bolts 34 and upper pivot bolts 36 the heads 38 of which are recessed in annular seats 40 formed in the inner faces of the sides 30 and 32. Pivoted on the bolts 34 and 36 respectively, are substantially rectangular, lower latch plates 42 and upper latch plates 44 that are retained on the bolts 34 and 36 by lock nuts or the like 46. These latch plates 42 and 44 are provided with notches 48 and 50 in their free rear longitudinal edges 52 and 54 that frictionally engage the upper rung 18 of the lower section 12 and the lower rung 22 of the upper section 14 to retain the anchor members in a fixed position on their respective ladder sections.
Extending outwardly from the forward sides 56 of the upper anchor members 28, are pivot bolts 58, the heads 60 of which frictionally engage annular seats 62 provided in the inner faces of the forward sides 56. These bolts 58 receivably engage nuts 64 for attaching the upper ends of a pair of substantially rectangular locking plates 66 to the upper anchor members 28. The outer longitudinal side edges 68 of these plates 66 are formed with transverse notches 70 that terminate adjacent finger grips 72 integrally formed with the inner longitudinal side edges 74 of the locking plates 66. The notches 70 frictionally and lockably engage outwardly projecting bolts 76 that are carried by the forward sides 78 of the lower channelled anchor members 24. These latest bolts 76 receivably engage retaining nuts 80 and are

also provided with enlarged head portions 82 that engage annular recesses 84 provided in the inner faces of the forward sides 78.

In practical use of the present ladder sections 12 and 14 as a step ladder, the locking plates 66 are disengaged from the bolts 76 and nuts 80 so that the sections 12 and 14 form a pair of upwardly converging elements that are hinged at their upper ends as shown best in Figure 2 of the drawings. In this position, a length of chain 86 connects selected upper rungs of the sections to permit only limited spreading of ladder sections.

To retain the sections 12 and 14 in position for use of the same as an extension ladder, the upper section 14 is pivoted upwardly, and the locking plates 66 engaged with the bolts 76 to hold the sections 12 and 14 in a longitudinally aligned and extended position as shown in Figure 1.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claim.

Reference is now directed to Figure 6 wherein for the purpose of illustration, there is disclosed the present ladder hinge in slightly modified form. In this embodiment, resilient or fabric wear pads or strips 88 are secured by rivets or the like 90 to the faces of the latch plates 42 and 44 that oppose the anchor members 24 and 28 to protect the anchor members 24 and 28 from marring and to afford the necessary frictional attraction between the pads 88 and anchor members 24 and 28 to prevent slippage of the latch plates 42 and 44 relative to the side rails.

Having described the invention, what is claimed as new is:

- A removable ladder hinge comprising first and second substantially rectangular sleeves, each of said sleeves having a rear wall, inner and outer side walls and a forward wall, a hinge joining the rear walls of said sleeves, a pivot pin projecting outwardly from the forward wall of said first sleeve and disposed at right angles to said hinge, 10 an elongated and flat latch member having first and second end portions, the first end portion of said member being received on said pin and contacting the forward wall of said first sleeve for swinging movement in a plane parallel to said 15 hinge, a threaded lug projecting from the forward wall of said second sleeve, the second end portion of said member having a notch for receiving said lug, a nut threaded on said lug for clamping the second end portion of said member against the 20 forward wall of the second sleeve, a threaded rod projecting from the inner side wall of each sleeve, flat rung engaging arms received on said rods, and further nuts threaded on said rods and clamping the rung engaging arms against the 25 inner side walls of said sleeves.

OSCAR E. NEHLER.
